CLAIM

The ornamental design for a furniture stand, as shown and described.

DESCRIPTION

FIG. 1 is a perspective view of the furniture stand showing my new design;

FIG. 2 is a front view of the furniture stand;

FIG. 3 is a rear view of the furniture stand;

FIG. 4 is a left view of the furniture stand;

FIG. 5 is a right view of the furniture stand;

FIG. 6 is a top view of the furniture stand; and,

FIG. 7 is a bottom view of the furniture stand.

The broken line portion of the figure drawings is included to show portions of the article that form no part of the claimed design.

1 Claim, 7 Drawing Sheets
